UNITED STATES PATENT OFFICE.

WILLIAM SCHAAKE, OF PITTSBURGH, PENNSYLVANIA, ASSIGNOR TO WESTINGHOUSE ELECTRIC & MANUFACTURING COMPANY, A CORPORATION OF PENNSYLVANIA.

DEVICE FOR TROLLEY-CONDUCTORS.

1,374,528.

Specification of Letters Patent. Patented Apr. 12, 1921.

Application filed March 9, 1918. Serial No. 221,389.

To all whom it may concern:

Be it known that I, WILLIAM SCHAAKE, a citizen of the United States, and a resident of Pittsburgh, in the county of Allegheny and State of Pennsylvania, have invented a new and useful Improvement in Devices for Trolley-Conductors, of which the following is a specification.

My invention relates to devices for trolley conductors and particularly to approaches for frogs, crossings and similar conductor attachments.

One object of my invention is to provide a device of the above-indicated character that shall be simple and durable in construction and economical to manufacture.

Another object of my invention is to provide an approach for trolley-conductor devices that shall comprise a relatively small number of parts, be readily transportable as a unitary structure and be readily mounted in operative position on a trolley conductor by the use of a simple tool, such as a hammer.

In practising my invention, I provide a removable extension member for a frog or other trolley-conductor device to take up the shocks and wear thereto incident to the passage of trolley contact members and which is so related to the frog and conductor, by the engagement of relatively broad surfaces, as to provide a rigid and efficient mounting for the same.

Figure 1 is a top plan view of a portion of a trolley frog embodying my invention; Fig. 2 is an end view of the device, as shown in Fig. 1; and Fig. 3 is a side view, partially in section, of the device shown in Figs. 1 and 2.

A frog 1, for attachment to trolley conductors 2, the approaches to only one end of which are shown, comprises channel portions 3 of substantially U-section, in which the converging conductors 2 are disposed and to which the latter may be attached in any suitable manner. An extension member 4, preferably of malleable material, projecting from each of the approaches to the frog 1, but only one of which is shown, has a channel portion 5 for embracing the conductor 3, a flat end face 6 that engages the end of the approach to the frog, and a centrally disposed web portion 7 disposed in the channel 3 above the conductor 2. An inclined upper edge 8 of the member 4 is adapted for co-operation with a wedge member 9 having a

similarly inclined face 10. Lugs 11, projecting from the ends of the portions 3, are provided with longitudinal grooves 12 for the reception of transverse flanges 13 of the wedge member 9. The member 4 is provided with a laterally projecting tongue 14 that projects through a slot 15 in the member 9. When assembled at the factory, the members 4 and 9 are placed in this relation and the tongue 14 is slightly bent in order that the members may be transported as a unitary structure. In mounting my device, it is placed in the position shown in Fig. 3 and the wedge 9 driven into rigid relation to the lugs 11 and the member 4, after which an extension 17 on the member 4 is turned up, as indicated by broken lines, to prevent loosening of the wedge.

When in operative position, the wedging pressure is exerted throughout a considerable portion of the conductor 2 by reason of the engagement of the relatively long web portion 7 with the same. A readily transportable unitary device of extreme simplicity and ruggedness, and which may be readily and firmly mounted with the aid of a hammer or similar tool, is thus provided.

While I have shown and described a particular form of my invention, changes may be made therein without departing from the spirit and scope thereof, as set forth in the appended claims.

I claim as my invention:

1. An approach for a trolley frog comprising a trolley-conductor-engaging extension member disposed adjacent to the frog and having an inclined plane face, a wedge member engaging the plane face of the extension member and a member on the frog for co-operation with the wedge member to assist the latter in holding the extension member rigidly against the conductor.

2. An approach for a trolley frog comprising a trolley-conductor-engaging extension member disposed adjacent to the frog, and having an inclined plane face, a wedge member engaging the plane face of the extension member, a member on the frog for co-operation with the wedge member to assist the latter in holding the extension member against the conductor and a member on the extension member adapted to be turned into interlocking relation with the wedge member.

3. An approach for a trolley frog com-

- prising a trolley-conductor-engaging extension member disposed adjacent to the frog and having an inclined plane face, a wedge member engaging the plane face of the extension member, said wedge member having an aperture therein, a member on the frog for coöperation with the wedge member to assist the latter in holding the extension member against the conductor and a member on the extension member disposed in said aperture and adapted for interlocking the wedge member and the extension member.
4. A trolley-conductor device comprising a body member having a wedge-receiving portion, a renewable approach member, and a longitudinally-slidable wedge to be driven between said members to clamp the approach member in position.
- 20 5. An approach for a trolley frog comprising a conductor-engaging extension member, a member disposed thereon, said members together being disposed between a portion of the frog and the trolley conductor and means whereby a thrust movement of the one of said members with respect to the other rigidly positions said extension member.
6. In a device for a trolley conductor, the combination with a body member engaging the conductor and means for supporting the body member, of a removable member adjacent and constituting an approach to the body member and adapted to embrace the

conductor, said removable member having an inclined plane face, a wedge member engaging the said plane face of the removable member, a lug on the body member co-operating with the wedge member to hold the removable member rigidly in position, and means for locking the wedge member and the removable member in position.

7. A trolley-conductor device comprising a body member of substantially channel shape for the reception of a conductor, said body member having a wedge-receiving portion, an approach member having a tongue projecting into the end of said channel and a wedge coöperating with said wedge-receiving portion and said tongue to clamp the approach member in position.

8. A trolley-conductor device comprising a body member, an approach member and a wedge member coöperating with said members to clamp said approach member in position.

9. A trolley-conductor device comprising a body member for the reception of a conductor and a longitudinally-slidable wedge to be driven between the body member and the conductor in the direction of the longitudinal axis of the conductor for holding the latter in position.

In testimony whereof, I have hereunto subscribed my name this 28th day of Feb. 1918.

WILLIAM SCHAAKE.
